ATTORNEY

UNITED STATES PATENT OFFICE.

ALWIN F. SOUTER, OF HACKENSACK, NEW JERSEY, ASSIGNOR TO E. & J. BASS, INC., A CORPORATION OF NEW YORK.

DESIGN FOR SALT SHAKER OR SIMILAR ARTICLE.

Application filed April 16, 1924. Serial No. 9,294. Term of patent 3½ years.

To all whom it may concern:

Be it known that I, ALWIN F. SOUTER, a citizen of the United States, and a resident of the city of Hackensack, county of Bergen, State of New Jersey, have invented a new, original, and ornamental Design for Salt Shaker or Similar Article, of which the following is a specification, reference being had to the accompanying drawing, forming a part hereof.

The drawing shows an elevational view of the salt shaker or similar article.

I claim:

The ornamental design for salt shaker or similar article substantially as shown.

ALWIN F. SOUTER.

Witnesses:

JOHN M. COLE,
M. BRANDT.
